UNITED STATES PATENT OFFICE.

PATRICK A. O'BRIEN, OF BOSTON, MASSACHUSETTS, ASSIGNOR TO WILLIAM J. CARLIN, OF BOSTON, MASSACHUSETTS.

DEVICE FOR HOLDING CHARTS OR THE LIKE.

No. 847,434.

Specification of Letters Patent. Patented March 19, 1907.

Application filed January 15, 1906. Serial No. 296,080.

To all whom it may concern:

Be it known that I, PATRICK A. O'BRIEN, a citizen of the United States, residing at Boston, in the county of Suffolk and State of Massachusetts, have invented an Improvement in Devices for Holding Charts or the Like, of which the following description, in connection with the accompanying drawings, is a specification, like letters on the drawings representing like parts.

My invention relates to devices for holding charts or the like, and particularly to means for conveniently and effectively holding maps, charts, or other like objects in an extended position upon the wall of a school-room, lecture-hall, or other place where it is desired to exhibit them.

My invention has, among other objects, the production of a map or chart holding device which may be readily adjusted within reasonable limits to give suitable hanging support to a chart of any width, permitting the latter to be readily and easily hung up or taken down, as desired.

My invention has particular application to the holding of charts or maps in a school-room or lecture-hall. It is usual to mount such maps upon a roller similar to an ordinary curtain-roller and provide the same with fixtures similar to ordinary curtain-fixtures, the latter secured to a backboard or base which is usually removably secured to the wall of the room. It has been customary to provide a special backboard with permanently attached fixtures thereon for each map, the different widths of maps with different lengths of rollers making the fixture non-interchangeable. Through the use of my invention a single backboard permanently secured to the wall, if desired, with a single set of fixtures may be employed for a variety of different widths of maps, thereby saving needless expense.

My invention will be best understood by reference to the following description, when taken in connection with the accompanying illustration, of one specific embodiment thereof, while its scope will be more particularly pointed out in the appended claims.

In the drawings, Figure 1 shows a map hung in position upon a hanger or holding device embodying one form of my invention. Fig. 2 shows, on an enlarged scale, partially

broken away, a portion of the track-support belonging to the device shown in Fig. 1; and Fig. 3 is a section on the line 3 3 in Fig. 2.

Referring to the drawings, and to the particular embodiment of my invention there illustrated, the hanger or holding device there shown is provided with a track-support which herein is shown comprised in two separate but similar pieces *a a*. These may be constructed in any suitable shape and of any suitable material, but I prefer in practice to form them of elongated strips of sheet metal each having its upper and lower sides *b* turned over, as best shown in Figs. 2 and 3, to provide guideways for and to suitably retain in place adjustable hangers *c* and *c'*, which resemble, generally, the hanging bracket of a curtain-fixture.

The supports *a a* are provided with any suitable means, such as the screw-holes shown, by which they may be fastened in a horizontal position upon a backboard *A* the latter being permanently secured or otherwise fastened to the wall of the school or other room. By constructing the supporting member in two parts they may be fastened to the board, with their ends abutting or at any desired distance apart, and thereby increase or diminish the range of adjustment obtainable from the holding device to any desired extent. It will be obvious that they may be made up in standard strips of moderate length and three or more of them arranged in series, so that by shifting the hanger *c* from one support to the next adjacent one they may be made to hold a chart *M* of any width from the smallest to the largest.

The hanging members or brackets are each mounted upon a base *d*, which has the elongated laterally-extended feet *e* underlying the overturned sides *b* of the track-support, so that the hanger can be moved lengthwise the same while effectually retained in place, whatever position be given it. Upon the hanger-base is formed a lug *f*, into which is threaded a set-screw *g*, the end of which may be made to engage with any one of a series of corrugations or serrations in the bottom of the trackway, these being readily formed in the illustrated embodiment by merely punching up a series of projections *n* from the bottom of the strip.

When the set-screw is loosened, the hanger may be shifted to any position within the limits of the supporting-strip and at the desired point may be secured by merely turning the set-screw to engage the bottom of the support, which forces the feet *e* out against the sides *b* of the supporting-strip, as seen in Fig. 3, and firmly locks the hanger in position.

- 10 The hanging member has an aperture *i*, provided with an open mouth *j*, after the usual fashion of curtain-holding brackets and of suitable size to engage with the flattened stem, which is usually employed at one end 15 of the map-roller *R*. The other hanger *c* (not shown) has the usual closed aperture, as is customary in curtain-fixtures, for receiving the opposite and rounded stem of the roller. The mouth *j* of the opening in the fixture *i* is slightly contracted, so as better to retain the same in position, the mouth, however, at its entrance, as well as the mouth and the entire aperture on its inner face, being preferably beveled, so that the stem if 20 pushed toward the mouth of the opening will naturally tend to find its place within the same.

When this device is employed, the base or backboard *A*, of suitable length to carry the 30 widest maps to be exhibited, may be permanently secured upon the wall of the room instead of removably secured thereto, as heretofore. The track-supports *a a* are then screwed in a horizontal position to the face 35 of the backboard. This single and permanently-secured fixture carrying the adjustable sliding brackets may then be used to hang maps of varying width, each of which requires to be provided only with the usual 40 roller-fixture and without the necessity of individual brackets or other supporting means therefor.

All the parts of this device may, if desired,

be nickelated or otherwise suitably finished, so that when in position upon the wall of a 4 room it will serve as an ornamental fixture.

While I have herein shown and described one form of my invention, it will be understood that the same is in no wise limited to the details or form and arrangement of parts 5c disclosed, but that extensive modifications may be made therein without departing from the spirit of my invention.

I claim—

1. A chart-holding device comprising a 55 backboard, two separated but aligned supporting members, each consisting of sheet metal having upper and lower overturned edges, and having formed integral therewith a series of horizontally-disposed corrugations, and a hanging member or bracket adapted to be received in each support for longitudinal movement therein, and provided with means to engage with said corrugations.

2. A chart-holding device comprising a 60 backboard, a pair of spaced but aligned supporting members each formed of sheet metal and provided with overturned edges forming a trackway, and further provided with integral corrugations struck up from the body of 65 said member, and a hanging bracket for each support adapted to receive a chart or map, and provided with a base adapted to be received in said overturned edges of the support, and further having a set-screw adapted 70 to be adjustably engaged with the desired corrugations.

In testimony whereof I have signed my name to this specification in the presence of 75 two subscribing witnesses.

PATRICK A. O'BRIEN.
